UNITED STATES PATENT OFFICE.

GEORGE WILLIAM DAVIS, OF PUTNEY, VERMONT.

DOWEL-MAKING MACHINE.

1,427,073.

Specification of Letters Patent. Patented Aug. 22, 1922.

Application filed March 1, 1920. Serial No. 362,323.

To all whom it may concern:

Be it known that I, GEORGE W. DAVIS, a citizen of the United States, and a resident of Putney, county of Windham, and State 5 of Vermont, have invented a new and Improved Dowel-Making Machine, of which the following is a full, clear, and exact description.

This invention relates to means for forming circular rods or dowels, and has reference more particularly to a machine adapted for forming circular wooden dowels from stock which is square or irregular in cross section.

15 An object of this invention is to provide a dowel making machine which is simple in construction.

Another object of this invention is to provide a dowel making machine in which the 20 stock is always exactly centered while engaging the cutting head.

A further object of this invention is to provide a dowel making machine so constructed that in case of breakage of stock 25 in the cutting head, said stock may be easily removed.

A still further object of the invention is to provide a dowel making machine in which the machine can be reversed so that 30 the stock is withdrawn after partly entering the knives.

A still further object of this invention is to provide cutting knives held in the support in such a manner that they may be 35 resharpened repeatedly and can be used in the machine until they are completely worn out.

Reference is to be had to the accompanying drawing forming a part of this specification in which it is understood that the 40 drawing illustrates only one example of the invention, and in which

Figure 1 is a side elevation of the dowel making machine.

45 Figure 2 is a section on the line 2-2 of Figure 1, said section being on an enlarged scale.

Figure 3 is a section on the line 3-3 of Figure 1.

50 Figure 4 is a top view of the dowel making machine.

Figure 5 is an elevation of the cutting head on a large scale.

Figure 6 is a fragmentary elevation on

a large scale of one of the cutting knives 55 attached to the cutting head.

Figure 7 is a fragmentary end view of the knife shown in Figure 6.

Figure 8 is a central section view through the cutting head.

Figure 9 is a perspective view, and Figure 10 is a sectional view of the stock guide.

Referring to the accompanying drawing by numerals, 10 indicates the main frame of the machine which is preferably in the 65 form of a square box open at both ends, and provided at its lower end with a base 11. An L-shaped standard is composed of a horizontal leg 12 which extends across opposite sides of the top of the box 10, and 70 is fastened thereto by means of bolts 13, and a vertical leg 14 which is semi-circular at the top so as to receive a second semi-circular member 15 having flanges 16 fastened to the leg 14 by means of bolts 17 so 75 as to form a split bearing in which is rotatably mounted the axle of a cutting head to be hereinafter described.

This cutting head is composed of a circular face plate 18 on which is radially 80 fastened by means of bolts 19 a plurality of knife supports 20, said knife supports being preferably four in number. Each knife support is preferably substantially rectangular in cross section, and is provided on one of the 85 faces perpendicular to the face plate 18, with an oblique longitudinal slot 21 forming a shoulder 22 which receives one side of a knife 23, said knife being held securely in position in said slot 21 by means of a plate 90 24 fastened to said support 20 by means of the bolts 19, said plate 24 having a flange 26 which co-operates with the shoulder 22 in clamping said knife securely in position.

Thus each knife is positioned radially with 95 respect to the face plate 18, and in a plane slightly at an angle to the plane of said face plate, and each knife is provided with an inner cutting edge 23a. A pulley 27 is formed on the surface of the face plate 18 100 opposite the knives 23, which is adapted to receive a belt 28 connected to any suitable power means not shown, which will cause the rotation of said face plate. A circular hole 29 passes co-axially through the face 105 plate 18 and the pulley 27, and is adapted to receive a tube 30 which is provided on one end with an annular integral shoulder 31.

The end of the tube 30 opposite the shoulder 31 is adapted to be received in the split bearing formed by the leg 14 and the semi-circular member 15, and is rigidly secured 5 in said split bearing by means of a bolt 32 which passes through the semi-circular member 15 and through a radial hole 33 in said tube 30. The tube 30 is adapted to form an axle about which the cutting head rotates, 10 and a sleeve 34 has an outside diameter such that said sleeve may be loosely received in the tube 30. This sleeve 34 serves as a guide for a dowel pin 35, after said dowel pin has been fed into the knives 23, and turned to a 15 rod which is circular in cross section by said knives, as the cutting head rotates. It is desirable that the sleeve 34 can be quickly removed in case the dowel pin 35 breaks and jams tight in said sleeve, and for this purpose the sleeve 34 is split diametrically 20 along a considerable portion of its length, and it is then cut at right angles to the axis of said sleeve in such a way that a semi-circular member 36 is formed which is 25 provided with a tongue 37 engaging a similarly shaped groove 38 in the sleeve 34. This semicircular member 36 is held in place securely with the tongue 37 engaging the groove 38, by means of the bolt 32, which, 30 after passing through the tube 30, engages a longitudinal slot 39 in said semicircular member. Thus by unscrewing the bolts 17 and 32, the end of said bolt 32 will be disengaged from the slot 39, and upon lifting 35 the member 15 and the semicircular member 34 out of position, the broken dowel pin can be removed. The knives 23 are so clamped by means of the plates 24 that their cutting edges 27 will be at different radial 40 distances from the center of the dowel pin as said pin is fed through the sleeve 34, (see Fig. 5) so that each knife will take a new cut from the dowel pin stock as the cutting head is rotated.

45 In order to feed the rough stock into the knives 23 as said knives are rotated by the cutting head, feed wheels 40 and 41 are provided adjacent said knives, so that they will be rotated in opposite directions, and with 50 their peripheries in contact by a mechanism to be hereinafter described. It should be understood that in the subsequent description of the mechanism connected with the feed wheels 40 and 41, that similar feed 55 wheels 40^a and 41^a are provided to receive the dowel pin 35 after it has been properly cut by the knives 23, and that the mechanism for operating the wheels 40^a and 41^a is identical to and similarly positioned as the 60 operating mechanism for the feed wheels 40 and 41. However, the feed wheels 40^a and 41^a are provided with an annular semi-circular groove 42^a instead of a V-shaped annular groove 42 in each of the feed wheels 65 40 and 41. The grooves 42, register and are

adapted to receive the corners of a rough piece of stock 43. These wheels 40 and 41 are rigidly secured on shafts 44 and 45 respectively which are substantially vertical, and have fixed to them on each of their lower ends a helical gear 46, said gears being arranged in position on each side of a transverse horizontal shaft 47, on which is secured a suitable worm 48 which engages the teeth of the helical gears and rotates 75 them in opposite directions.

It is desirable to have the shafts 44 and 45 so journaled that the feed wheels 40 and 41 will ordinarily adjust themselves to the shape of the rough stock fed into the V-shaped notches 42, and for this purpose each shaft is provided with a vertically disposed bar 49, and each bar is provided at its lower end with a transverse flange 50 in which is journaled the lower end of each shaft adjacent the helical gears 46. A flange 51 is formed at the upper end of one of the bars 49, and a flange 51^a is formed at the upper end of the other of said bars 49. The flanges 51 and 51^a form bearings for the upper ends 90 of the shafts 44 and 45. The lower end of each bar 49 is pivotally mounted to the inside surface of one wall of the box 10 by means of pin 52, so that the upper flanges 51 and 51^a of said bars 49 may be rocked independently about pins 52, so that the distance between the feed wheels 40 and 41 may be varied, thus allowing for irregularities in the size of the rough stock 43. In order to hold the wheels 40 and 41 together resiliently 100 so that they may spread apart when it is necessary to take a larger size piece of stock 43, the upper flanges 51 and 51^a of the bars 49 are enclosed by a frame 53 which is substantially rectangular in shape, and is also guided as 105 it moves when the bars 49 are rocked, by means of a vertical flange 54 formed on the upper end of one side of the box 10. A set screw 55 is screwed through one side of the frame 53 and engages a slot 56 formed in the flange 51. An adjusting screw 57 passes through the opposite side of the frame 53 and is provided on its inner end with a shoulder 58 which supports a spring 59, the inner end of said spring, being set in an inner recess 60 formed in the flanges 51^a. This spring 59 is continuously in compression and serves to press the two feed wheels 40 and 41 together so that sufficient traction is obtained with the rough stock 43 to feed it into the knives 23 as the shafts 44 and 45 are rotated, and the compression in said spring may be adjusted by means of a hand wheel 61 fixed to the outer end of the adjusting screw 57.

120 It is desirable to give the bars 49 an initial adjustment about the pins 52 so that the rough stock will be fed into the knives 23 substantially co-axial with the face plate 18, and it is also desirable to have the feed 125 130

wheels 40 and 41 separated an equal distance from the axis of said rough stock 43 when irregularities occur in the size of said rough stock. In order to accomplish these results, an arm 62 is pivoted at one end by means of a bolt 63 to one wall of the box 10 between the shafts 44 and 45. The end of the arm 62 opposite the bolt 63 is formed into a bearing 64 in which is secured a shaft 10 65 by means of a radial pin 66, said shaft passing through a wall of the box 10 and having rotatably mounted on the inside of said box, a disc 67. In order to allow the arm 62 to rock about the pivot 63, an arcuate slot 68 is provided in the wall of the box 10 so as to give play to the shaft 65 in said slot. In order to adjust the shaft 65 in any desired position in the slot 68, a bolt 69 passes through the arm 62 between the pivot 20 63 and the bearing 64, and said bolt also passes through an arcuate slot 70 in the wall of the box 10. When the shaft 65 has been placed in its desired position, in the slot 68, the nut on the bolt 69 is tightened so that the 25 arm 62 is clamped tightly against the outside face of the side of the box 10, thus holding said arm securely in the adjusted position. The end of each of a pair of links 71 is pivoted diametrically opposite on the disc 67 30 by means of pins 72, and the other end of each link is pivoted to one of the bars 49 by means of a pin 73. Thus the wheels 40 and 41 are adjusted by loosening the nut of the bolt 69 and swinging the arm 62 about, 35 the pivot 63 until the rough stock is fed into the knives 23, so as to be coaxial with the face plate 18, after which the nut on the bolt 69 is tightened and by a similar proceeding the wheels 40^a and 41^a are adjusted so that 40 they will receive the finished dowel as it is delivered from the sleeve 34. When different sized stock is fed into the wheels 40 and 41 said wheels will separate by rotating the disc 67 and the parallel links 71 will 45 make sure that the wheels separate an equal distance from the axis of the rough stock, so that said rough stock will still be accurately centered with respect to the face plate 18 regardless of its size. 50 It is desirable to have the direction of rotation of the wheels 40, 41, 40^a and 41^a, reversible, so that in case the dowel 35 breaks and jams in the knives 23 or in the sleeve 34, that their rotation can be quickly 55 reversed so as to withdraw the broken dowel from the machine. For this purpose a pair of pulleys 74 is mounted on the shaft 47 midway between the two worms 48. Each pulley is provided on one of its faces with a 60 frusto-conical section 75, each pulley 74 being so placed on the shaft 47 that the frusto-conical sections 75 will be placed adjacent each other. The pulleys 74 are mounted on an enlarged section 76 of the 65 shaft 47, and a sleeve 77 is also mounted upon this section 76 serving to space the two pulleys 74 apart. The pulleys 74 are prevented from moving axially by means of a pair of collars 78 fixed to the section 76 adjacent the faces of the pulleys 74 which are 70 opposite the frusto-conical sections 75. A key 79 passes through the sleeve 77 and the section of the shaft 76, so as to hold said sleeve 77 in position and also to engage keyways 80 in a collar 81 which is thus slidably 75 but not rotatably mounted upon the collar 77 between the frusto-conical sections 75. The collar 81 has inner frusto-conical surfaces 82 which register with the frusto-conical sections 75, and form a friction clutch 80 connecting the pulleys 74 and the shaft 44. In order to move the collar 81 axially so as to engage one or the other of the pulleys 74, the collar 81 is provided with an annular groove 83 which is engaged by an annular 85 shoulder 84 on a split collar 85 held together by means of bolts 86. One semicircular member of the split collar 85 is pivotally mounted to a shifting bar 87 by means of a bolt 88, and said bar extends transversely 90 between the sides of the box 10 and is pivotally mounted at one end to a lug 89 formed on the inside of one side of the box 10 by means of a bolt 90. The end of the shifting bar 87 opposite the bolt 90 is slidably 95 mounted in and extends through a horizontal slot 91 formed in the wall of the box 10 where it has a circular section 92 which is loosely journaled in a block 93, and is secured thereto by means of a nut 94. 100 Any suitable means may be provided to shift the block 93, horizontally, but preferably as shown a horizontal link 95 is pivoted at each end to a shifting lever 96 by means of a bolt 97, said levers being in turn pivoted on to the outside of the box 10 by means of bolts 98. The link 95 passes through a slot 99 in the block 93, and is clamped therein by means of bolts 100 which press the two parts of the block formed by the slot, closely together against the link 95. In order to prevent axial movement of the shaft 47, safety collars 101 are provided inside the box 10 on the shaft 47, and safety collars 102 are provided on the ends of the shaft 47 outside 115 the box 10, and the ends of the shaft 47 are journaled in bushings 103 provided in the walls of the box 10, said bushings being provided so that the section 76 of the shaft 47 can be assembled by moving said shaft 47 120 axially through the walls of the box 10. Each of the pulleys 74 should be rotated in opposite directions, and for this purpose a belt 105 leads from one of the pulleys 74 and passes over idlers 106 and 107 to a 125 pulley 108 fixed to a power shaft 109 supported in any suitable manner such as by bearings 110. A second belt 111 leads from the remaining pulley 74 over idlers 112 and 113, and after having its runs crossed, is 130

placed in position on the pulley 108. Both the belts 105 and 111 pass through an opening in one side of the box 10, and brackets 105^a and 111^a have pivotally mounted on them, arms 105^b and 111^b which rotatably support the idlers 106, 107, 112, and 113, and said arms may be rocked about their pivot and may be secured in any adjusted position by means of bolts 105^c and 111^c which operate in arcuate slots 105^d. Thus the tension in the belts may be adjusted so that slipping of the belts is reduced to a minimum. Also the two belts 105 and 111 will be operated in opposite directions from the same pulley 108.

In order to guide the rough stock 43 into the V-shaped notches of the feed wheels 40 and 41, an arm 114 is fastened to the outside of the box 10 by means of bolts 115, and the upper end of said arm 114 is provided on its inner surface with a channel shaped groove 116 and a slot 117 passes transversely through the arm 114 in the groove 116. A bolt 118 passes through the slot 117 of the arm 114 and said bolt is provided with a square head 119 which engages the sides of the groove 116 so as to prevent the bolt 118 from turning when a nut 120 is screwed on to the end of said bolt opposite the head 119. An arm 121 has at one end a recess 122 which receives the upper end of the arm 114 and through the arm 121 the bolt 118 passes so as to position said arm 121 substantially at right angles to the arm 114, and the arm 121 is turned upwardly at its upper end and is formed into a V-shaped guide 123 which is so positioned that the rough stock 43 is guided exactly into the V-shaped grooves 42 in the feed wheels 40 and 41.

In order to inspect the inside of the box 10, an opening 124 is provided in one side of said box and a door 125 is hinged in said opening by means of hinges 126. By opening this door 125, the hand may be inserted and adjustments made of any of the interior mechanism.

In operation the rough stock 43 is placed in the guide 123 and moved axially toward the feed wheels 40 and 41 until it is engaged by said wheels and moved axially into the knives 23 which are being rapidly rotated by means of the belt 28. These knives cut off the corners of the rough stock 43 as it passes through them, and the resulting dowel pin 35 then passes through the sleeve 34 and out between the delivery wheels 40^a and 41^a which assist the feed wheels 40 and 41 in moving the rough stock 43 axially through the knives. In case of breakage of the dowel as it passes through the sleeve 34, the semicircular member 36 is removed by unscrewing the bolts 17 and 32, thus allowing the removal of the broken dowel. The traction between the feed wheels 40 and 41

and the discharge rolls 40^a and 41^a is adjusted by the handle 61 of the adjusting screw 57 which increases or decreases the compression of the spring 59. The feed wheels 40 and 41 and the delivery wheels 40^a and 41^a are rotated by means of the shafts 44 and 45 which are journaled in the flanges 50, 51, and 51^a of the vertical bars 49. The helical gears on the lower ends of the shafts 44 and 45 engage the worms 48 which are rotated by the shaft 44. The belts 105 and 111 lead from the power shaft 109 and rotate each of the pulleys 74 in opposite directions as said power shaft is rotated. The friction collar 81 between the pulleys 74 is operated by means of the shifting levers 96 on the outside of the box 10 so that when the friction collar 81 engages one of the pulleys 74, the shafts 47, 44, and 45 will be operated in one direction while if the levers 96 are shifted so that the friction collar 81 engages the other of said pulleys 74 the direction of rotation of the above mentioned shafts will be reversed so that the dowel pin 35 will be withdrawn in case of breakage. The wheels 40, 41, 40^a, and 41^a are properly centered with respect to the knives 23 by moving the arm 62 about the pivot 63, and then tightening the nut on the bolt 69 with the arm 62 in the proper adjusted position. When the wheels 40, 41, 40^a, and 41^a spread apart or closed together to accommodate varying sizes of stock, the discs 67 will rotate and the parallel links 71 will move the aforementioned wheels an equal distance from the axis of the stock, thus always maintaining the stock properly centered with respect to the knives 23.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim as new and desire to secure by Letters Patent:

1. In a dowel making machine, a plurality of knives supported substantially radially, means for rotating said knives, means for feeding material in one direction between said knives as they are rotated, said knives acting to form the material into a rod which is circular in cross section, means for withdrawing the material from said knives, resilient means for maintaining the material centrally located with respect to the knives, regardless of its size, and means, whereby a broken dowel may be quickly removed from said knives.

2. In a dowel making machine, a face plate provided with a centrally located hole, a plurality of knives supported substantially

- radially on said face plate, means for rotating said face plate, means for feeding material through said hole between the knives, said knives acting to form the material into 5 a rod which is circular in cross section, and a sleeve loosely fitted in said hole, said sleeve having a removable section whereby to permit the removal of a broken dowel therefrom.
- 10 3. In a dowel making machine, a support, bars pivotally mounted at their lower ends on the support and having bearings at their ends, shafts mounted in the bearings of the bars and carrying feed rolls, means for operating the shafts, a frame surrounding the upper bearings of the shafts and having means engaging one of the bearings, an adjusting screw mounted in the frame, and a spring between the screw and the other 20 bearing.
4. In a dowel making machine, a support, bars pivotally mounted at their lower ends on the frame and having bearings at their ends, the upper bearings being recessed, 25 shafts mounted in the bearings and carrying feed rolls at their upper ends, means for operating the shafts, a frame surrounding the upper bearings, a screw mounted in the frame and engaging the recess of one bearing, a spring arranged in the recess of the other bearing, and an adjusting screw mounted in the frame and engaging the spring.
5. In a dowel making machine, a frame, 35 pivotally mounted bars in the frame, revoluble shafts mounted in the bars and carrying feed rolls, an adjustable rockable bearing a non-revoluble shaft carried by the bearing, and a member loosely mounted on the shaft, and links connecting the member 40 with said bars.
6. In a dowel making machine, a frame having a curved slot, bars pivotally mounted in the frame, revoluble shafts mounted in the bars and carrying feed rolls, a pivoted bearing on the frame, means for adjusting the bearing a shaft carried by the bearing and extending through the slot of the frame, a member loosely mounted on the shaft, and links connecting said member with the bars. 50
7. In a dowel making machine, a frame having curved slots, bars pivotally mounted in the frame, revoluble shafts mounted in the bars, and carrying feed rolls, an arm pivoted to the frame, a bolt passing through the arm and one of the slots of the frame, a shaft carried by the free end of the arm and extending through the other slot of the frame, a disk loosely mounted on the shaft, and links connecting the disk with the bars. 55
8. In a dowel making machine, a revoluble cutter head feed rolls on opposite sides of the cutter head, a transverse shaft, means for operating the rolls from the shaft, spaced pulleys on the transverse shaft and each having a conical section, a collar mounted to slide but not to turn on the shaft and having a conical section at each end, a shifting bar pivoted at one end and secured to said collar, a sliding block with which the other end of the shifting bar is connected, pivoted levers, one at each end of the machine a link connecting the levers and secured to the sliding block, and means for operating the pulleys in opposite directions. 60 70 75

GEORGE WILLIAM DAVIS.
